TELEPHONE REPEATER

Francis Alley Hubbard, Maplewood, N. J., assignor to American Telephone and Telegraph Company, a corporation of New York

Application September 1, 1933, Serial No. 687,854

11 Claims. (Cl. 179—170)

This invention relates to telephone repeaters, and more particularly to two-way repeaters of the so-called "directional" type, intended for use on irregular two-wire telephone lines.

5 One object of the invention is to obtain an effective gain from the repeater larger than would be permitted by the impedance balance or "return loss" between the lines to which the repeater is connected and their respective balancing networks.

10 A second object is to simplify the attenuation pads used in this type of repeater, and improve the means of switching them.

15 A further object is to minimize the harmful effects of noise on the circuit upon the operation of the repeater.

20 In attaining these objects, the applicant, in general, modifies an ordinary type of two-way telephone repeater by introducing an attenuation

25 pad in one side or the other of the repeater, so that there is always sufficient loss in the singing path through the repeater to prevent objectionable circulating currents, although one side of the repeater is giving a substantial effective gain.

30 These pads are under the control of a voice-operated relay, the direction of operation of which depends on the direction from which telephonic currents are reaching the repeater. Thus the pad is removed from the side of the repeater

35 which is transmitting the telephonic currents, and an equal pad is inserted in the other side. Electrical biasing means are provided which hold the relay in the direction last operated until the arrival of telephonic currents of a predetermined

40 strength from the other direction. Since noise currents may be strong enough to reverse the relay during brief pauses in speech, a slow-release relay is provided, also voice-operated but without bias, to reduce the sensitivity of the main relay during speech to a point where noise currents will be unable to operate it.

45 The principle of operation of the "directional repeater" has been described in two copending applications, Serial Numbers 687,880 and 687,874, which are assigned to the same assignee as the present application. It may be briefly stated as follows:

50 It is well known that with the ordinary type of telephone repeater used on two-wire lines, the gain that can be obtained is determined by the impedance similarity between the lines to which the repeater is connected and the corresponding artificial lines or balancing networks with which the repeater is equipped. The measure of the 55 impedance similarity at any frequency between

one of the lines and its network is called the "return loss" at that frequency. If at any frequency the sum of the repeater gains in the two directions is greater than the sum of the return losses of the two lines against their networks, the repeater will sing, that is, set up a sustained oscillation, at that frequency.

5 Ordinarily a single repeater is given the same gain in both directions, since substantially equal transmission is desired for both subscribers. 10 However, gain is required in only one direction at a time, and the gain in the other side of the repeater may be reduced, provided the conditions are interchanged every time the direction of conversation changes. This can be done by means 15 of voice frequency devices, arranged to recognize the direction from which telephonic currents are reaching the repeater, and to modify the gains of the two sides of the repeater accordingly. The gain in the direction of transmission may then 20 be given a value which would result in singing if both sides of the repeater had that value; if the sum of that gain and the reduced gain in the other side is substantially less at all frequencies than the sum of the return losses, satisfactory results will be obtained. A repeater 25 so arranged is called a "directional repeater."

It would be possible to disable entirely the amplifying element in the reverse direction, as is usually done in such devices as echo suppressors. 30 This has the disadvantage, however, that as weak speech sounds, particularly initial consonants, may be unable to operate the device, considerable distortion and reduction in intelligibility 35 may result from the loss of these sounds. I prefer to make the reduction in gain, in the reverse direction, just sufficient at all frequencies to provide a reasonable margin against singing, and against the distortion which results from a near approach to singing. Speech sounds which are 40 too weak to operate the device will then be attenuated, but not entirely lost.

The device described herein is similar to one of the embodiments disclosed in application Serial Number 687,874 already referred to, with certain 45 distinctive differences which will appear in the following detailed description, and which make the device more satisfactory under certain conditions. The description is to be read with reference to the accompanying drawings, which indicate diagrammatically and in part schematically the circuits and apparatus involved. Like reference characters designate like parts in the two figures of the drawings, which represent two different embodiments of the invention, each of 50 55

which has certain advantages under particular conditions.

In each of the figures of the drawings, A and A' indicate the telephone lines to which the repeater 5 is connected, and B and B' the corresponding artificial lines or balancing networks. C and C' are balanced transformers or hybrid coils as commonly used in this type of repeater, and D and D' are the amplifying elements of the repeater for 10 the two directions of transmission. E and E' are amplifier-detectors of any well-known form, connected across the conductors F and F', respectively, and responsive to telephonic currents flowing therein. The outputs of these amplifier-detectors are connected differentially to the polarized relay I, in such a way that the direction of 15 operation of this relay is determined by the relative magnitudes of the rectified currents flowing in the windings M and M'. Since the amplifier-detectors E and E' are substantially similar, the 20 direction of operation of relay I will be determined by the relative magnitudes of the telephonic voltages applied to their inputs. The armature of relay I serves to short-circuit one 25 or the other of the attenuation pads H, H', thus providing the full gain of the amplifier D or D', while reducing the gain in the opposite direction 30 by the insertion of the pad. The pads as shown are designed to give greater losses at high and low frequencies than in the middle of the voice range, since the return loss of loaded cable circuits, with which such repeaters are most commonly used, has such a characteristic with frequency. The transformers T, T' in Figure 1 are 35 used if necessary to avoid possible noise induction from the lines due to the presence of the impedance H or H' in one wire only.

The system as just described constitutes a "directional repeater", substantially as disclosed 40 in application Number 687,874, already referred to. An important difference lies in the arrangement which permits the use of a single pad in each side of the repeater, instead of two pads in each side. It is necessary to the proper functioning 45 of the device that the input terminals of the amplifier-detectors E, E' shall be connected to the circuit at a point intermediate in the loss of the pads H, H'. The reason for this requirement lies in the fact that, as there will ordinarily 50 be a considerable degree of unbalance between the lines and their respective networks, telephonic currents from either line will affect both amplifier-detectors, by transmission through the hybrid coils. For example, consider the circuit 55 shown in Fig. 1 of the drawings, but assume that the inputs of the amplifier-detectors, E, E' were connected directly across transformers T and T', respectively. Suppose telephonic currents arrive 60 from line A. A portion of these currents will enter amplifier-detector E; the remainder will be amplified by amplifier D, and will enter hybrid coil C'. A portion of these amplified currents will pass through coil C' and enter transformer T'. If the loss in this passage through coil C', 65 which depends upon the impedance balance or return loss between line A' and network D', is less than the amplification of amplifier D, the currents entering transformer T' may be greater than those originally entering T. This condition 70 might occur without causing the repeater to sing. In this case the rectified current in winding M' would be greater than that in winding M, and the relay would reverse, putting the amplification in the wrong direction. As soon as this 75 happened, the currents flowing through amplifier

D would be reduced by the pad H, and the portion entering transformer T', and thus affecting amplifier-detector E', would be smaller than those affecting E, and relay I would reverse once more. Relay I would, therefore, swing rapidly back and forth as long as speech continued, an obviously unsatisfactory condition.

Suppose, however, that the amplifier-detectors E and E' were connected directly across the amplifiers D and D', respectively. The condition 10 of hunting described in the last paragraph could not then exist; but it might be impossible to reverse the device at all. Suppose the amplifier-detectors so connected in the circuit of Fig. 1, and the armature of relay I against its left-hand 15 contact, as indicated. Speech currents from line A will then receive amplification, and will leave the relay in that position, since the currents reaching amplifier-detector E' will be attenuated by pad H', and will be less than those 20 entering E. In the case of currents arriving over line A', however, if the loss through coil C is less than the gain through amplifier D', the input to amplifier-detector E will be greater than that to E', and relay I will be held in the wrong position. 25

To avoid these conditions, it is desirable to be able to connect the amplifier-detectors at suitable intermediate points within the pads. To do this where single pads of the resonant type are used requires special arrangements, such as those 30 illustrated in the drawings. In Fig. 1 relatively high impedance retardation coils J and J' are shown connected in parallel with the pads H and H', respectively. The voltage drop across each retardation coil is, of course, the same as that 35 across the corresponding pad. By connecting the amplifier-detector to a suitable intermediate point on the retardation coil, the desired intermediate position with respect to the pad can be secured. It is preferred to bring out taps at 40 several intermediate points on the retardation coils, as indicated, so that the position of the amplifier-detectors can be adjusted to suit the particular conditions encountered. For example, if it were known that the balance against 45 one of the lines would, in general, be substantially better than against the other, it might be of advantage to use different settings on the two retardation coils.

In Fig. 2 of the drawings is shown a different 50 method of connecting the pad into the circuit, and of obtaining the desired intermediate point for the amplifier-detectors. The pad is connected inductively, through the transformer U, instead of directly; and to avoid the necessity 55 of using the insulating transformer T, the line windings are divided equally between the two sides of the circuit, as indicated, thus providing a longitudinally balanced circuit. To obtain the desired points of connection for the amplifier-detectors, it would be possible to bring 60 out taps on one or both of the line windings of the coils U and U'. As this would result in somewhat complicated and expensive coils, however, the method indicated in Fig. 2 is preferred. In 65 this, each of the coils U, U' is of the familiar hybrid coil construction, similar, in general, to coils C and C', with the center point of each line winding accessible. The input of amplifier-detector E is connected to these center points on coil U, and similarly with E' to coil U'. The input impedance of each amplifier-detector must 70 be widely different from the impedance of the pad as measured through the coil U: It is pre- 75

ferred to make the amplifier-detector impedance much higher than the pad impedance.

The position of the amplifier-detector E with respect to the loss in the pad, when connected as indicated, depends upon the relative impedances in the two directions from the line terminals of coil U, that is, upon the input impedance of amplifier D and the composite impedance of line A, network B and amplifier D' as seen through the hybrid coil C. If these two impedances are equal, substantially the same voltage will be applied to the input of the amplifier-detector E whether the secondary of transformer U is short-circuited or not. Under these conditions all the loss of pad H is effectively beyond the point of connection of amplifier-detector E, which as already explained may result in instability of relay I and unsatisfactory operation. The same is of course true of the other side of the repeater. If, however, the impedance looking towards coil C is substantially less than the input impedance of amplifier D, the voltage applied to the amplifier-detector E will be less when the secondary of coil U is closed through pad H than when it is short-circuited, which means that under these conditions the amplifier-detector is connected, as desired, at an intermediate point in the loss of pad H, the exact position depending on the relation between the impedances. Therefore, a variable resistance V is provided bridged across the circuit, as indicated, for the purpose of making the impedance on that side of coil U less than the input impedance of the amplifier D. By adjusting the value of resistance V, the point of connection of amplifier-detector E can be effectively brought to any desired intermediate point in the loss of pad H, as was done in the circuit of Fig. 1 of the drawings by means of the taps on retardation coil J. Resistance V will of course introduce a loss in the circuit, but it is a fixed loss which can be compensated by an increase in the gain of amplifier D.

The same discussion applies to the other side of the repeater, in which resistance V' is provided for the same purpose as resistance V. It is desirable that the loss introduced by resistances V and V' be substantially the same, so that the gains of the amplifiers D and D' may be substantially equal.

Another feature of the invention is the provision of adjustable electrical bias to hold the armature of relay I in the direction last operated, whether or not telephone currents are arriving from that direction, until the arrival of such currents of a predetermined strength from the other direction. The biasing flux must of course be reversed in direction when the armature of the relay changes from one contact to the other. This could be accomplished directly through the contacts; but in this case the biasing current must be made and broken by the contacts, and the resulting clicks would make it impossible to connect the contacts directly to the pads. An alternative method is to rely on the pull of the permanent magnet of the relay to hold the armature against whichever contact it approaches. This leaves the relay contacts free of direct current, so that they may be connected to the pads, and it has the advantage of simplicity. It lacks however, the reliability and ready adjustability of an electrical bias. It is preferred to use the electrical bias, which it is proposed to obtain by auxiliary means without causing clicks by making or breaking any appreciable

current through the relay contacts. Fig. 1 and Fig. 2 of the drawing show somewhat different means of accomplishing this, each of which will have advantages under certain conditions.

In Fig. 1 the bias is controlled by an auxiliary relay K, similar to relay I and adjusted to be as closely like it as possible in operating characteristics. The operating windings N and N' are connected in series with the operating windings M and M', respectively, of relay I, and the biasing windings Q and Q' in parallel with the biasing windings P and P', respectively, of relay I. When relay I is operated to the left, by telephonic currents arriving from line A, relay K is simultaneously operated to the left, and biasing currents flow through the left-hand contact of relay K and through windings P and Q in parallel to ground. The fluxes due to these biasing currents are such as to hold both relays firmly against their left-hand contacts until the arrival of telephonic currents of a predetermined intensity from line A', when both relays operate to the right, breaking the current through biasing windings P and Q, and sending current through the opposite biasing windings P and Q' which are so poled as to hold the relays against their respective right-hand contacts. The intensity of the telephonic currents required to reverse the relays, that is, the sensitivity of the device, is largely determined by the strength of the biasing fluxes: the biasing currents of the two relays can be independently adjusted by the resistances Z and Z'.

S and S' represent lamps, to give the maintenance forces a visual indication of the direction in which the device is operated. If the relays are performing correctly, the lamps will usually light alternately several times per minute. If one of them burns steadily for a considerable period, it is an indication that something is probably wrong, and the maintenance forces will investigate.

The biasing arrangements indicated in Fig. 2 of the drawings are somewhat different. The auxiliary relay is omitted, and the current for the biasing windings P and P' is supplied from battery Y, through the adjustable resistance Aa, lamps S and S', and the plate circuits of vacuum tubes W and W' respectively. The grids of tubes W and W' are connected to the right-hand and left-hand contacts, respectively, of relay I. Battery X supplies a negative potential to the armature of relay I, of sufficient magnitude when applied to the grid of either of the vacuum tubes W or W' to block the flow of plate current in that tube. However, on account of the very high impedance of the grid circuit of a vacuum tube, the current made and broken by the contacts of relay I will be too small to cause appreciable clicks in the transmission circuit. When the armature of relay I is against its left-hand contact, the potential battery X will block the plate current in tube W', and hence biasing winding P' will carry no current. Current will flow, however, through winding P, lamp S, and the plate circuit of vacuum tube W to ground. Relay I will thus be held against its left-hand contact, and lamp S will be lighted. Similarly, when telephonic currents of sufficient strength arrive from line A' to operate relay I to the right, current will flow through winding P' of relay I, lamp S', and the plate circuit of vacuum tube W' to ground, while the current through winding P will be cut off by the application of the potential of battery X to the grid of tube W. Thus the relay armature will be held against its right-hand contact, lamp S will be extinguished and lamp S' lighted. The

magnitudes of the biasing currents may be adjusted by means of the resistance Aa .

A third feature of the invention is the provision of means for minimizing the objectionable effects of noise on the circuit. The usual characteristic of noise currents in a telephone system is that they are fairly steady in intensity, as compared with the wide fluctuations of voice currents. It will seldom happen that noise currents will be comparable in intensity with the peaks of voice currents, which correspond to vowel sounds; but they may occasionally be greater than intermediate portions of speech currents corresponding to consonants. Since the directional repeater as described herein is at all times sensitive to telephonic currents from both directions, it may happen that steady noise from the direction opposed to that from which speech is reaching the repeater may be able to reverse the relay during pauses in the speech, or when the speech currents are of low intensity. While the next succeeding vowel sound would usually be able to operate the device in the right direction, the reversal, though brief, would introduce a certain amount of undesirable clipping and distortion of the consonant sounds.

To minimize this effect, it is proposed to provide, in the cases where noise may be serious, a device which will reduce the sensitivity of the main relay while speech currents of a certain intensity are flowing, and will maintain that reduced sensitivity for a brief period sufficient to bridge the usual time between vowel sounds in speech. This reduction in sensitivity will be great enough to make it unlikely that noise currents can cause operation, so that during normal speech there will seldom be a reversal due to noise, except in case of a pause long enough for the sensitivity-reducing device to release. There will, of course, be some sacrifice in speed of reversal when speech from the other end of the circuit begins immediately, especially if the initial speech currents are of low intensity, due to consonant sounds. This will result in some slight increase in clipping of initial consonant sounds, with consequent distortion. Under severe noise conditions, however, this may be considerably less serious than the effect of frequent noise reversals. There will be no chance of false operation due to the reduction in sensitivity, since this reduction is the same for both directions of transmission.

Two slightly different embodiments of this arrangement are shown in the two figures of the drawings, each having certain advantages under particular conditions. In Fig. 1, L designates a slow-release relay, the sensitivity of which is considerably less than that of the polarized relays I and K . The windings O and O' are connected to the outputs of amplifier-detectors E and E' , respectively, in series with the corresponding operating windings of relays I and K . When relay L operates, it shunts the resistances R and R' around the operating windings M , N and M' , N' of relays I and K , thereby reducing the sensitivity of those relays by such an amount that they are not likely to be operated by noise currents. Due to the slow-release feature of relay L , obtained by any well-known means such as a copper band around the pole piece, the low sensitivity condition of relays I and K will be maintained for a brief period after the currents in the windings of relay L have fallen below the value necessary to hold it operated. This will

serve to protect the repeater from false reversals due to noise during brief pauses in speech, such as spaces between words or syllables.

Assume that speech currents are arriving from line A . If these currents are of sufficient intensity to operate relay L , they will first operate relays I and K , since relay L is much less sensitive. As long as normal speech continues from line A , relay L will be held operated by the rapidly recurring peaks of current representing vowels, 10 Now assume that the speech from A ceases, and immediately speech from A' begins, before relay L releases. The adjustment of relay L with respect to relays I and K is such that if the speech currents are too weak to reverse relays I and 15 K in their condition of reduced sensitivity, they will also be too weak to hold relay L operated. If the initial speech currents from A' are weak, therefore, relay L will release after a brief interval, and restore relays I and K to full sensitivity; 20 if the speech currents are strong enough to hold relay L operated, they will reverse relays I and K even at the low sensitivity. Thus the only interference with proper operation on speech will be on initial currents of low intensity, for 25 the brief period of holding for which relay L is adjusted.

The arrangement in Fig. 2 of the drawings is very similar, though the point of application differs somewhat. In this figure, Bb designates a 30 slow-release relay, whose sensitivity is adjusted with respect to that of relay I along the lines just discussed; that is, the current necessary to hold it operated is less than that required to operate relay I at its minimum sensitivity. The 35 windings of relay Bb are connected in series with the operating windings of relay I . When relay Bb operates, its armature short-circuits a certain part of the resistance Aa , thereby increasing by a predetermined amount the biasing current 40 through winding P or P' of relay I , and thus decreasing the sensitivity of that relay. The amount of this change in sensitivity, as well as the maximum sensitivity, may be adjusted by means of resistance Aa . The operation of relay 45 Bb in Fig. 2 of the drawings is exactly analogous to that already explained with regard to relay L in Fig. 1.

While the invention has been disclosed, for the purposes of illustration, in certain specific embodiments, it will be understood, that it may be embodied in other and different forms without departing from the spirit of the invention which is defined in the appended claims.

What is claimed is:

1. In a two-way telephone repeater including two one-way paths adapted for transmission in opposite directions, a voice-operated polarized relay adapted to transfer attenuation from one path of the repeater to the other, electrical means for biasing the said polarized relay in the direction last operated without passing current through the contacts of the said relay, and means for so adjusting the said bias that a predetermined value of telephonic current will be required to operate the said polarized relay in the reverse direction.

2. In a two-way telephone repeater including two one-way paths adapted for transmission in opposite directions, a voice-operated polarized relay adapted to transfer attenuation from one path of the repeater to the other, a second voice-operated polarized relay similar to the first-mentioned relay and adjusted to operate substantially simultaneously therewith, and adjustable

means controlled by the contacts of the said second-mentioned relay for applying to both of said relays biasing current adapted to hold the relays in the direction last operated until the arrival 5 from the opposite direction of telephonic currents greater than a predetermined intensity.

3. In a two-way telephone repeater including two one-way paths adapted for transmission in opposite directions, a voice-operated polarized relay adapted to transfer attenuation from one path of the repeater to the other, a thermionic device controlled by the position of the armature of the said relay and adapted to supply bias to the relay to hold it in the direction last operated, 10 and means for so adjusting the magnitude of the said bias that a predetermined value of telephonic current will be required to operate the said relay in the reverse direction.

4. In a two-way telephone repeater, two separate unidirectional paths for transmission in the two directions, an amplifying element and an attenuation element in each path, a voice-operated device associated with each path, switching means differentially connected to the two voice-operated devices and adapted to remove one or the other of the said attenuation elements from its associated path, and adjustable means for connecting each voice-operated device to its associated path at any desired intermediate point 30 within the corresponding attenuation element.

5. In a two-way telephone repeater, two separate unidirectional paths for transmission in the two directions, an amplifying element in each path, an attenuation element inserted in series 35 in each path, a voice-operated device connected across each path, adjustable means for so locating the point of connection of each voice-operated device to its associated path that a predetermined portion of the loss of the corresponding attenuation element is effectively on each side of the said 40 point of connection, and means differentially controlled by the two voice-operated devices to short-circuit one or the other of the two attenuation elements in accordance with the direction of arrival 45 of telephonic currents at the repeater.

6. In a two-way telephone repeater, two separate unidirectional paths for transmission in the two directions, an amplifying element in each path, an attenuation element inserted in series 50 in each path, an impedance element in parallel with each attenuation element, a voice-operated device associated with each path, means for connecting each voice-operated device from any of several points on the associated impedance element to the opposite side of the associated path, and means differentially controlled by the two 55 voice-operated devices to short-circuit one or the other of the two attenuation elements in accordance with the direction of arrival of telephonic currents at the repeater.

7. In a directional repeater for use on irregular two-wire telephone lines, including two one-way paths adapted for transmission in opposite directions and a voice-operated switching system adapted to transfer attenuation from one path of the repeater to the other, the method of protecting the repeater against false operation due to noise, which consists in reducing the sensitivity of the switching system when the received telephonic currents exceed a certain maximum in-

tensity, and maintaining the reduced sensitivity for a predetermined period after the currents fall below that intensity.

8. In a directional repeater for use on irregular two-way telephone lines, including two one-way paths adapted for transmission in opposite directions and a voice-operated switching system adapted to transfer attenuation from one path of the repeater to the other, the method of protecting the repeater against false operation due to 10 noise, which consists in reducing the sensitivity of the switching system when the received telephonic currents exceed a certain maximum intensity, and maintaining the reduced sensitivity after the currents fall below that intensity for a 15 period corresponding approximately to the interval between words in average speech.

9. In a two-way repeater including two one-way paths adapted for transmission in opposite directions, a voice-operated switching device adapted 20 to transfer attenuation from one path of the repeater to the other, means for reducing the sensitivity of the said device when the received telephonic currents exceed a certain maximum intensity, and means for restoring the original sensitivity 25 of the device at a predetermined interval after the telephonic currents fall below that intensity.

10. In a two-way telephone repeater including two one-way paths adapted for transmission in 30 opposite directions, a voice-operated device responsive to telephonic currents reaching the repeater and adapted to transfer attenuation from one path of the repeater to the other, means for holding the said device in the direction last operated 35 until the arrival from the opposite direction of telephonic currents greater than a predetermined intensity, a voice-operated relay of substantially lower sensitivity than the said device and adapted to reduce the sensitivity of that device, and means to restore the original sensitivity 40 of the said device a predetermined time after the telephonic currents have decreased below the value necessary for the operation of the said relay.

11. In a two-way telephone repeater, two separate unidirectional paths for transmission in the two directions, an amplifying element and an attenuation element in each path, a voice-operated device associated with each path and responsive to telephonic currents flowing therein, adjustable means for connecting each voice-operated device to its associated path at any desired intermediate point of the corresponding attenuation element, a polarized relay differentially connected to the two voice-operated devices and 55 adapted to remove one or the other of the attenuation elements from the associated path, adjustable electrical means requiring no current through the contacts of the said relay for holding the relay in the direction last operated until the 60 arrival of the repeater of telephonic currents greater than a predetermined minimum intensity, voice-operated means for reducing the sensitivity of the said relay when the telephonic currents are greater than a certain maximum intensity, 65 and means for restoring the original sensitivity of the said relay a predetermined time after the telephonic currents have become less than the said maximum intensity.
